Patented Sept. 13, 1910.

UNITED STATES PATENT OFFICE.

FRANK O. KUCERA, OF TOBIAS, NEBRASKA

CHECK OR DRAFT PROTECTOR.

970,341.

Specification of Letters Patent. Patented Sept. 13, 1910.

Application filed November 30, 1909. Serial No. 530,672.

To all whom it may concern:

Be it known that I, FRANK O. KUCERA, a citizen of the United States, residing at Tobias, in the county of Saline and State 5 of Nebraska, have invented new and useful Improvements in Check or Draft Protectors, of which the following is a specification.

The present invention is an improvement 10 in check or draft protectors, and its especial object, stated in general terms, comprehends the production of an extremely simple and effective device for embossing that portion of a check or draft whereon the figures indicating 15 the amount thereof are written, in such a manner as to prevent alteration of the same.

The invention also comprehends the production of a device of the above mentioned 20 character which may readily be attached to one of the covers of a check or draft book in position to emboss the checks or drafts contained therein, and which may, with equal readiness, be detached when the checks or 25 drafts have become exhausted and applied to a new book.

Furthermore, the invention resides in the production of a protector, as above described, which will serve to hold a blotter in 30 place against the cover, so that the blotter may be utilized in the ordinary manner after the check or draft has been filled in.

Finally, the invention comprehends the production of a protector which may be constructed so cheaply as to enable it to be either furnished gratis by a bank when an account is opened with the same, or purchased at an extremely low cost.

A structural embodiment of the invention 40 is illustrated in the accompanying drawings, whereof:

Figure 1 is a perspective view of the device *per se*. Fig. 2 is a similar view showing the device applied to a check book. 45 Fig. 3 is a side elevation, showing a check in position to be operated upon. Fig. 4 is a plan view, showing the embossed check.

Reference being had to said drawings, and to the characters marked thereon, A designates in a general manner a check book of the ordinary type, and B the protector designed for attachment thereto.

As shown in Fig. 1, the protector comprises a pair of metallic plates 1 and 2 connected together by a hinge 3, each plate being provided upon its inner face with a die

4 having an embossed working surface 5. These dies may be in the form of separate plates attached to the plates 1 and 2, or they may be formed integral with said plates, 60 according as may be preferred. The embossings may be likewise of any suitable character; in the present instance, one die is formed with teeth, and the other with registering openings wherein the teeth project when the two dies are forced together, as hereinafter described, the object being to mutilate that portion of the check or draft received therebetween.

The upper plate 1 has a somewhat greater 70 width than the lower plate 2, and its side edges are bent laterally inward toward each other, as indicated by the numeral 6, said edges lying in spaced parallel relation to the outer face of plate 1, thereby providing 75 an open-ended pocket 7 through which the upper cover 8 of book A is adapted to be inserted, as shown in Fig. 2. This pocket also receives the inner end of a blotter 9 which is arranged against the inner face of 80 said cover, the free or outer portion of the blotter being thus held in position to blot the check proper when the book is closed. The side edges of plate 1, after having first been bent inward, as above described, are 85 then bent in the reverse direction, as indicated by the numeral 10, the spaces between the bent portions 6 and 10 receiving the side edges of a cover 11 of card board, leather, or other suitable material, which may, if desired, have printed thereon the names of the depositor, the bank, or the manufacturer of the device. Illustration of this feature is considered unessential and is, therefore, omitted.

In positioning the device, the outer cover is slipped through the pocket 7 until the lower plate 2 rests upon the stub portion of the checks, the front or outer edge of that plate lying directly adjacent the cut away 100 line of perforations which separates the checks proper and stubs. After a check has been filled in in the ordinary manner, and subsequently blotted, it may be folded backward so as to dispose that portion thereof 105 wherein the figures indicating the amount of the check are written directly above the working surface of the lower die. The cover of the book is then partially closed, as shown in Fig. 3, thereby bringing the upper die into position directly above the lower die. When this has been done, the upper

plate is struck sharply, thus causing the portion of the check between the dies to be embossed or scored by the working surfaces thereof, (see Fig. 4.) Upon opening the book, the embossed check may be torn out in the ordinary manner, this operation being facilitated by the weight of the lower plate upon the stub portion of the check, and by the arrangement of the front edge of said plate directly adjacent the line of perforations. If considered advisable, a portion of one of the dies may have embossed upon its working surface, in addition to the scoring, the words "Not over", or some similar phrase, the other die having the same phrase cut in intaglio upon its working surface.

Further description of the invention, its manner of operation, and its advantages, is considered unnecessary, in view of the foregoing, beyond the fact that the embossing may be made upon the check or draft after the same has been detached from the corresponding stub, if such be considered preferable.

I claim as my invention:

1. A check or draft embossing device comprising a pair of connected die-bearing mem-

bers, one of said members being formed with a pocket through which the cover of a check or draft book is adapted to be inserted.

2. An embossing attachment for books having detachable leaves comprising a pair of connected die-bearing members, one of said members having its side edges bent inwardly toward each other and in spaced relation to the body portion thereof, to constitute a pocket through which the cover of the book is adapted to be inserted.

3. A device of the class specified, comprising a pair of hinged metal plates provided upon their inner faces with coöperating dies, one of said plates having its side edges bent inwardly toward each other, and in spaced relation to the outer face thereof, to constitute a pocket, and a cover for said pocket having its side edges connected to the first mentioned edges.

In testimony whereof I have hereunto set my hand in presence of two subscribing witnesses.

FRANK O. KUCERA.
